UNITED STATES PATENT OFFICE

132,809

DESIGN FOR A TEXTILE FABRIC

Andrew Flory, New York, N. Y., assignor to Frank Associates, Inc., New York, N. Y., a corporation of New York

Application May 11, 1942, Serial No. 106,858

Term of patent 3½ years

To all whom it may concern:

Be it known that I, Andrew Flory, a citizen of the United States, residing at New York city, in the county of New York and State of New York, have invented a new, original, and ornamental Design for a Textile Fabric, of which the following is a specification, reference being had to the accompanying drawing, forming part thereof.

The drawing shows a plan view of a textile fabric illustrating my new design, a complete unit of said design being embraced by the intersecting section lines, said unit being repeated longitudinally and transversely throughout the entire length and width of the fabric.

I claim:

The ornamental design for a textile fabric, substantially as shown and described.

ANDREW FLORY.
